HORN

Filed Nov. 24, 1923

FIG. 2.

BY *Denison & Thompson.*
ATTORNEYS

UNITED STATES PATENT OFFICE.

WILLIAM SPARKS, OF JACKSON, MICHIGAN, ASSIGNOR TO SPARKS-WITHINGTON COMPANY, OF CLEVELAND, OHIO, A CORPORATION OF OHIO.

HORN.

Application filed November 24, 1923. Serial No. 676,749.

This invention relates to certain improvements in horns or signaling devices.

The primary object of this invention is the production of an improved structure whereby a more desirable, efficient and satisfactory lubrication of the cam carrying shaft and its bearings is effected.

Other objects and advantages relate to the details of the structure referred to, all as will more fully appear from the following description taken in connection with the accompanying drawings in which:

Figure 1 is a top plan view of the horn or signaling device.

Figure 2 is a section on line 2—2, Figure 1.

Figure 3 is a section on line 3—3, Figure 1.

Figure 4 is a longitudinal section through Figure 1 taken at right angles to Figure 3.

The general structure of horn or signaling device here illustrated is the same as that disclosed in my co-pending application, Serial Number 493,498 filed August 18, 1921 and comprises a resonator —1—, a front diaphragm case section —2—, a diaphragm —3—, a rear diaphragm case section —4— formed with a pair of spaced openings for the reception of the respective threaded end portions —5— and —6— of a pressed metal U-shaped motor field or yoke —7—, the nuts —8— engaging the threaded ends of the field —7— to rigidly connect the same to the rear diaphragm section —4—.

The motor field —7— carries the usual pole pieces —9—, field coils —10— and commutator brushes —11— all as shown, described and claimed in Letters Patent issued to me October 12, 1920, Number 1,355,283.

The armature —12— of the motor is mounted upon the armature shaft —13— in the usual manner and the shaft —13—, has one end extending through the rear wall —14— of the motor field and its opposite end extending through an opening in the rear diaphragm case section —4—, and journaled in a manner to be hereinafter described.

The armature shaft —13— carries at a

point forward of the case section —4—, a cam or tooth member —15— adapted to contact when rotated with a projection or wear piece —16— upon the central portion 55 of the diaphragm to effect vibration of the latter upon rotation of the cam.

The cam may be held upon the armature shaft in any suitable way by means of a nut —17—.

The brushes —11— are adapted to contact with the commutator —19— upon the armature shaft.

For the purpose of effecting desired adjustment of the armature shaft —13— to 65 vary the relative position of the cam —15— and the wear piece —16— to thereby produce the desired displacement or vibration of the latter, I have illustrated an end thrust bearing, the broad claims for which 70 bearing are contained in my application Serial Number 493,498 and consisting of a bar —20— extending substantially parallel with the rear wall —14— of the U-shaped motor field and having one end —21— bent 75 at substantially right angles to the body of the bar and formed with the reduced portion —21— extended through an opening in the rear wall —14— so as to slide therein, but adapted to limit movement of the bearing in a direction longitudinal of the length of the bar.

Preferably, as illustrated, the bar —20— is of somewhat channel form and has one of its ends with a depressed portion —18— 85 adapted to receive and retain one end of a spring —22— positioned between the free end of the bar —20— and the rear wall —14—.

Preferably, the spring is disposed on the 90 opposite side of shaft —13— from the flanged end —21— that extends through the wall —14—.

Intermediate the spring and the flanged end —21—, the shaft —13— bears against 95 the bar —20— and for the purpose of moving the bar toward the wall —14—, I have provided a threaded stud —23— adapted to have an adjustable threaded engagement with the rear wall —14— and to extend 100 through the bar —20—.

This stud comprises an enlarged head

portion —24— provided with a slot for the reception of rotating means, the said head adapted to project through an opening in the case or cover —70— to permit adjustment without removal of the cover.

In order to effect predetermined fine degrees of adjustment and hold the parts frictionally interlocked at other times, I have provided a ratchet mechanism comprising a strap —26— which extends across the bar —20— and has its end bent at substantially right angles to its laterally extending portion so as to lie in substantial contact with the edges of the bar —20—.

The upper portion of this strap, or adjusting member is provided preferably, with a series of radially extending grooves or notches —30— adapted to conform with and receive a series of projections or teeth upon the lower face of the enlarged head —24— of stud —23—.

By forming these receiving grooves and projecting parts of desired size any predetermined quantity of adjustment may be effected by moving the stud —23— through a single notch or tooth or additional notches, should further adjustment be desired.

In order to prevent forward movement of the shaft —13— and to hold it in comparatively rigid position to prevent rattling during use, I have provided a spring member —31— as shown in the form of an elongated plate, having an intermediate bend, one end of which spring bar is mounted on the threaded end —5— of the motor field at the rear of the nut —8—, the opposite end of said bar contacting with the front end of the armature shaft —13—, the bar being so tensioned as to exert a thrust force upon said shaft tending to hold it in contact with the thrust bearing at the rear end of the shaft.

This spring and its arrangement constitute claimed subject matter of my co-pending application Serial Number 396,802 filed July 16, 1920.

In this construction of horn, it is heretofore been customary, as illustrated in my said co-pending applications and my said patent to form the rear diaphragm case section of dish-shape and with a substantially circular flat base or bottom wall —36— in which wall the forward portion of the armature shaft —13— is journaled.

In the present construction, for the purpose of lubricating the forward portion of the armature shaft and providing an efficient bearing for it, the circular flat bottom wall —36— is formed with a depressed portion —37— of somewhat rectangular form, the said depressed portion forming a chamber that is preferably somewhat deeper at the opposite ends of the rectangle and is comparatively shallow at its central portion and formed at its central portion with an

opening through which the armature shaft —13— extends, the opening being preferably of greater diameter than the shaft.

By making the depression shallow at its central portion, it is not necessary to lengthen the armature shaft to any appreciable extent in order to form the lubricant chamber for effecting lubrication of the bearing —38— for the armature shaft.

The bearing —38— is formed in a plate —39— that in this particular illustration is of somewhat rectangular form conforming to the shape of the chamber produced by depressing the portion —37— of the wall —36— and this plate is of the size preferably extending both laterally and longitudinally beyond the depressed portion to form a closed chamber except for the opening in the depressed portion —37— through which the armature shaft extends and for the bearing —38— which is formed in a circumferential flange pressed at right angles to the body of the plate —39— forming an elongated bearing surface.

In addition to the bearing and opening through which the armature shaft extends, the opposite longitudinal ends of the depressed portion —37— are formed with oil passages or openings —40— which lead to the chamber formed between the depressed portion —37— and the plate —39— and preferably this chamber contains a wick or sheet of felt or other lubricant-retaining material which surrounds the shaft —13—.

The plate —39— may be secured to the bottom wall —36— in any suitable way as by means of bolts or rivets —41— which extend through the plate in the bottom wall at the opposite ends of the plate.

It will be obvious that the bearing —38— and the shaft —13— may be readily lubricated through openings —40— at any time when the cover —70— is removed and the lubricant-retaining material in the chamber will maintain the shaft in lubricated condition for long periods of time.

Although I have shown and described a specific form and construction of the parts as illustrative of a perhaps preferred embodiment of my invention, I do not desire to restrict myself to the details of form, shape or arrangement of the parts for the reason that so far as I am aware, I am the first to form a wick or felt-containing chamber at the forward end of the motor shaft for lubricating the shaft bearing, and particularly when that chamber is formed by offsetting a portion of the bottom wall of the diaphragm case and closing the chamber by means of a plate that is formed with a bearing for the armature shaft.

I claim:

A horn structure comprising a rear diaphragm case section of dished form, and hav-

ing a generally flat circular rear wall provided with a central depressed portion, a plate rigidly and permanently secured across the forward side of the depressed portion to form a lubricant chamber, the rear part of the depressed portion being inclined inwardly from its edges towards the plate, a

shaft extending through said depressed portion and through said chamber, and said plate formed with a stationary bearing for 10 the shaft.

In witness whereof I have hereunto set my hand this 15th day of November, 1923.

WILLIAM SPARKS.
